DRYING AND/OR COATING APPARATUS

Edward E. Ekert, Rego Park, and Gerald R. Richards, Manhasset, N. Y., assignors to American Chicle Company, Long Island City, N. Y., a corporation of New Jersey

Application February 17, 1938, Serial No. 190,964

6 Claims. (Cl. 34—5)

The object of the present invention is to provide an apparatus for tumbling-drying and particularly in the presence of a coating material, such as a syrup, and for causing controlled air streams to be drawn through the tumbling body for withdrawing moisture and for conserving volatile constituents of the coating material and also solids, such as sugar dust when a sugar syrup is employed as the coating material.

10 The invention embodies the following principles:

(a) The use of a tumbling drum of screen material through which air is drawn to the material being dried, the air then passing to a collector;

15 (b) The use of a screen drum supported by vanes in such manner that the vanes control or bound individual streams of air;

(c) The support of an inner screen drum by vanes projected outwardly and carried by outermost rings between which the exhaust trough operates;

20 (d) Driving the device by a shaft at one end and supporting the device by rollers applied to flanged rings carried upon the periphery of the device.

The invention will be described with reference to the accompanying drawings, in which:

Figure 1 is a side elevation, partly broken away, illustrating an embodiment of the invention.

Figure 2 is an end elevation thereof.

Figure 3 is a reduced schematic end view, from the position of Figure 1, and partly broken away, showing the use of an electric heating element 35 to augment the drying effect of the air drawn through the device.

Figures 4 and 5 are perspective views of certain plates which may be carried by the sides of the drum and readily detached therefrom 40 for removing deposits of dry coating ingredients such as sugar.

Figure 6 is a sectional side elevation of the device taken on the line 6—6, Figure 7.

Figure 7 is a transverse sectional elevation 45 taken on the line 7—7, Figure 6.

Figure 8 is a fragmental sectional view on the line 8—8, Figure 6, showing one of the connections between a drum side and the removable plates.

50 Figure 9 is a similar sectional view on the line 9—9, Figure 6.

Referring to the drawings, it will be seen that the device comprises a supporting frame A having opposed horizontal side members 1 on each 55 of which is secured a set of two brackets 2.

Each bracket 2 carries a shaft 3 which rotatably supports a roller 4. The two sets of rollers 4 rotatably support the drying drum.

The drum comprises side plates 5, 5x, each plate carrying at its periphery a frusto-conical element 6, the two frusto-conical elements being spaced at their outer ends as shown more particularly in Figures 2 and 7. The frusto-conical elements 6 hold between them a plurality of wedge-shaped vanes in spaced relation, these 10 vanes being indicated at 7. Carried by the vanes at their inner ends is an annular screen 8. This screen is adapted to contain a tumbling material, for example such as the small units shown in Figure 6, for drying per se or for coating as 15 by use of a coating material from which the moisture or volatile constituents are to be withdrawn. The units shown are gum units.

Welded to side plate 5 is a bearing wheel 9 connected by webs or spokes 9x with a hub-like 20 central element 10 carrying a shaft 11 through which rotational movement may be imparted to the drum. The driving means illustrated in Figure 2 comprises a pulley 12 on shaft 11 adapted to be rotated by a belt 13 from a suitable source 25 of power.

The side plate 5x has welded or otherwise secured thereto a bearing wheel 14 which immediately contacts with a set of the rollers 4 as shown in Figures 1 and 7. The said bearing 30 wheel 14 may be reinforced by the webs 14x and within it is positioned a centrally apertured annular plate 15. The units to be coated may be inserted into the drum through the aperture of the said plate 15. If desired, a heating device 35 may be positioned within the drum. To this end, a standard 16 is shown secured to the frame A, the standard having a socket member 16x at its top to receive the lower end of a bent arm 17 extending into the drum through the aperture 40 of plate 15 and carrying at its end an electrical heating element generally indicated at 18. If desired, the heating element may be disposed exterior of the rotating drum and such an element is shown at 19, Figure 3, and including a 45 hood-like section 19x curved to correspond with the curvature of the drum periphery.

An air draft trough is carried by frame A, the main body of the trough being indicated at 20 and its discharge outlet at 20x. The trough body 50 is secured to the frame by means of transversely extending bracket arms 21 (Figures 1 and 2) and to each of the opposed side walls of the trough body is bolted a curved bar 22, the curvature conforming with that of the drum. This 55

bar is adapted to hold in position, in each case, a preferably yielding air-sealing strip 23 which may immediately contact with one of the plates 6. At each end of the trough body 20 there is secured by a threaded bolt and thumb nut 24 a supporting finger 25 for a sealing strip 26 of rubber or other flexible material, which sealing strip immediately contacts with the periphery of the drum, shown more particularly in Figure 6.

In the operation of the apparatus, uncoated gum units or other units to be coated are inserted into the drum through the opening in plate 15, and shaft 11 is rotated to impart rotation to the drum in the direction of the arrow.

During the rotation and/or prior thereto, the coating material, as, for example, a sugar syrup, will be poured upon the units to be coated. The rotation of the drum will carry the body of units upward to generally the position shown in Figure 6 the units tumbling in such upward movement, and their constant change in position and mutual contact effecting a uniform distribution of the coating material over their surfaces. During the tumbling movement of the units air will be drawn through them by the application of an exhaust to the discharge end of the trough 20. By reason of the association with the screen of the spaced vanes 7 individual streams of air laden with moisture and by any solid particles of the material, such as sugar, freed from the drum or the units themselves, will pass from the area of the tumbling body to the trough and thence via its discharge end to a suitable collecting medium for preservation of the valuable volatile constituents and solids. The vanes insure that streams of air drawn through the tumbling body will comprise the entire air-stream-creating-force of the suction device. The construction and arrangement of the elements comprising the device insure that there are no ineffective air by-passes. There is no waste because the suction is so controlled by the vanes and trough as to be applied only to the tumbling body of units undergoing coating.

It will be understood that deposits of solids will accumulate upon interior surfaces of the drum. In order to provide a ready and convenient means for collecting said deposits the innerinside faces of the drum have removably secured thereto a series of wedge-like plates. Those for end plate 5 comprise the segments 27 each formed near its top with key slots 28 for coaction with headed studs 29 carried by end plate 5 and each segment plate 27 near its pointed end may be slotted at 30 to receive a threaded stud such as 31, Figure 7. After a stud is inserted in the slot 30 of an appropriate plate a wing nut 32 may be applied. In removing these plates, the wing nuts will be removed and the plates successively moved inwardly so as to clear the edges of adjacent plates, this being possible because the headed studs will be so formed as to permit such movement. Each plate will then be moved toward the axis of the drum until the round key section of the slot registers with the headed stud, permitting removal of the plate.

The plates 27 x at the opposite side of the drum will each be formed with key slots 28 x and straight slots 30 x to receive detachable fastening elements similar to those applied to the removable plates 27, as will be understood without further explanation.

In the description of the operation set forth above, it has been considered that the screen will 75 contain gum units to be coated with a sugar

syrup from which the moisture and volatile ingredients will be withdrawn by suction or air through the tumbling material. However, the apparatus is adapted to treat any tumbling body for the removal of moisture therefrom or for the coating thereof with any suitable coating material. In any of these cases the air trough 20 may receive a forced draft of air which will pass through the vanes and screen and thence through the tumbling body, without any necessity for change in arrangement of the elements shown in the drawings. It will also be obvious that the trough 20 may be positioned above the tumbling body and therefore somewhat increased in area so that the vanes below the tumbling body will be exposed and the remaining vanes covered by the trough and sealed by a suitable instrumentality such as the sealing strips 26. When the trough is in superposed position relatively to the screen it may act as a suction device or as the discharge member for an expelled forced draft of air or gas capable of extra absorption.

In the coating of gum units of the character desired for chewing gum, the heating devices should be so designed and operated as not to raise the temperature of the tumbling material beyond a predetermined maximum. To this end the heating device or devices may be operated intermittently or continuously in accordance with the specific conditions to be met. Likewise, the air draft whether by suction or blast may be continuously or intermittently effected. When the coating is of laminated material, each coating may require specific control of the heating or air application in accordance with the characteristics of the specific coating material.

Having described our invention, what we claim and desire to secure by Letters Patent, is as follows:

1. A drying and coating apparatus comprising a rotary casing having side plates and a cylindrical screen forming with said plates a chamber for the reception of a tumbling material, a plurality of peripherally extending vanes carried by the casing and leading outwardly from said screen, means for rotating the casing with the screen and vane structure held thereby, and an air trough having effective communication with a plurality of said vanes at their outer ends during said rotation.

2. A drying and coating apparatus comprising opposed vertical plates, one of the plates having an axial aperture, bearing wheels carried by the plates, bearing rollers upon which the wheels rest, a plurality of peripheral radial vanes carried by the structure, a cylindrical screen disposed axially of the vanes and in contact therewith, a shaft secured to one of the plates, means for rotating the shaft, and means for effecting a forced draft of air, said means having effective communication with a plurality of said vanes at their outer ends during said rotation.

3. A device constructed in accordance with claim 2, in which the forced draft means comprises a trough-like member, and yielding sealing means carried by the trough-like member and in contact with said vanes during their movement.

4. A drying and coating apparatus for gum units, comprising opposed vertically disposed plates, one of the plates having an axial aperture, a plurality of spaced wedge-shaped vanes disposed peripherally of the plates, means cover-

ing the side edges of the vanes, said means being spaced to provide air passageways between the vanes, a cylindrical screen disposed inwardly of the vanes, a fixed air draft device having effective communication with a plurality of said vanes at their outer ends, and means for rotating the structure comprising said plates, screen, vanes and covering means.

5. A device constructed in accordance with claim 4, in combination with a plurality of de-

10 tachable facing plates for said vertically disposed plates of the apparatus.

6. An apparatus constructed in accordance with claim 4, in combination with electrical heating means supported in fixed relation to the rotating structure and supported opposite the air draft device.
